UNITED STATES PATENT OFFICE.

WILLIAM ROBINSON, OF MUSKEGON, MICHIGAN, ASSIGNOR TO THE W. G. NAGEL ELECTRIC COMPANY, OF TOLEDO, OHIO, A CORPORATION OF OHIO.

POLE-DISTRIBUTION RACK FOR TELEPHONE SYSTEMS.

No. 846,144.

Specification of Letters Patent.

Patented March 5, 1907.

Application filed May 3, 1906. Serial No. 314,947.

To all whom it may concern:

Be it known that I, WILLIAM ROBINSON, a citizen of the United States, and a resident of Muskegon, in the county of Muskegon and State of Michigan, have invented certain new and useful Improvements in Pole-Distribution Racks for Telephone Systems; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to electrical appliances, and has particular reference to insulating-brackets for receiving and holding in spaced relation the several pairs of wires of a telephone-cable immediately after they leave the distribution - box and preparatory to their extension to their several terminals.

The object of my invention is to provide a bracket of this class which is of simple and cheap construction and capable of having its size readily and easily increased or diminished to suit the number of lead-wires which it is desired to accommodate, and by which adequate capacity can be obtained with economy of space.

Another object is to provide a bracket that will readily accommodate a large number of wires leading out in substantially the same direction from the point of distribution.

The invention is fully described in the following specification and illustrated in the accompanying drawing, which is a view in perspective of a portion of a pole having a pole-house or distribution-box and a bracket comprising my invention secured thereto.

Referring to the drawing, 1 indicates a distribution-box such as is commonly used in telephone and telegraph systems, 2 an insulating-bracket comprising the features of my invention, and 3 a pole or other stationary object to which said box and bracket are secured.

The bracket 2 consists of the two end members or brackets 4, which are of L-shaped construction and securely fastened in spaced relation on the supporting-pole or object 3 by lag-screws 5 or in any other suitable manner. The brackets 4 are shown in

the drawing as being provided with flat sides which are set into gains in the pole; but these brackets may be made with curved sides so as to fit the pole without gaining. These members or brackets 4 have their shelves or outwardly-projecting portions preferably disposed toward each other and afford supports for one or more bolts or pins 6, as shown. Mounted on each bolt or pin 6, between the faces of the shelves of the brackets 4, are a plurality of insulating-spools 7, of porcelain or other suitable insulating material, the number of which is governed by the distance between said brackets or members 4 and the consequent length of the carrying-bolts. In the illustration the distribution-bracket is shown as provided with two bolts or pins 6, each carrying five insulating-spools, thus enabling it to accommodate ten pairs of wires 8, only one of which is shown in the drawing.

It will be apparent with this construction of bracket that any desired number of lead-wires may be accommodated by either changing the spacing of the end members 4 and the length of the bolts or pins 6 or by increasing or diminishing the number of said bolts carried by the bracket.

Having thus described my invention, what I claim as new, and desire to secure by Letters Patent, is—

1. A wire-distribution bracket, comprising in combination with a support, two spaced members secured to the support, a rod-like element connecting said members and held thereby in spaced relation to the support, and a plurality of insulating-spools carried by said element.

2. A wire-distribution bracket comprising in combination with a support, spaced members secured to the support and having outwardly-projecting portions, a plurality of rod-like members connecting said projecting portions of the spaced members, and a plurality of insulating-spools carried by each rod-like member.

3. A wire-distribution bracket, comprising spaced adjustable end brackets capable of being secured to a supporting member and having projecting portions, a plurality of pins connecting the projecting portions of the end brackets, and a plurality of insulating-spools carried by each pin intermediate the projections, substantially as described.

4. A wire-distribution bracket comprising spaced securing parts, means connecting said parts, and a plurality of abutting insulating-spools carried in axial alinement by said means.

5. A wire-distribution bracket comprising, in combination with a support, spaced L-shaped securing parts carried by the support, a plurality of pin members secured at their ends to said parts, and a plurality of insu-

lating-spools axially carried by said pin members, substantially as described.

In testimony whereof I have hereunto signed my name to this specification in the presence of two subscribing witnesses.

WILLIAM ROBINSON.
